Ben T. Emberton, 23700 Toy Ave., and Gaetano LaPenta, 22812 Lake Blvd., both of St. Clair Shores, Mich. 48079

Filed Mar. 26, 1969, Ser. No. 16,439

Term of patent 14 years

Int. Cl. D6—01

U.S. Cl. D33—17

FIG. 1 is a front elevational view of a holder for an elongated object embodying our new design;

FIG. 2 is another front elevational view thereof showing said holder in use;

FIG. 3 is a top plan view of FIG. 2;

FIG. 4 is a horizontal sectional view taken on line 4—4 of FIG. 2; and

FIG. 5 is a rear elevational view thereof.

The fragmentary showing in broken lines of an elongated object in FIGS. 2 through 4 and of a wall in FIGS. 1 through 4 is for purposes of illustration.

We claim:

The ornamental design for a holder for an elongated object, as shown and described.
